UNITED STATES PATENT OFFICE.

THOMAS W. DEMAREST, OF PITTSBURGH, PENNSYLVANIA.

PACKLESS BLOW-OFF VALVE.

Application filed January 5, 1920. Serial No. 349,556.

My present invention relates in general to valve devices, and more particularly, to drain valve structures, and has special relation to the provision of an improved form of packless drain valve mechanism wherein the valve itself is located within the vessel or cavity to be drained.

Fluid drain valves, in which the valve is located externally of the container to be drained, present certain disadvantages in that the inlet port of the valve body is at all times in open communication with such container and that the valve body on the one hand has to be made sufficiently strong to withstand any pressure occurring in the latter; and on the other hand such body being exposed to the weather is subject to atmospheric variations with the frequent result that when the temperature drops sufficiently the fluid contained in the valve body may freeze and burst it.

When, however, the valve itself is disposed inside of the container to be drained, it is not so subject to failures on account of the circumstances recited, since there is ordinarily no fluid in the valve body save at the time the container is being drained.

Moreover, in drain valves of both types, as heretofore constructed in practicable manners known to me, the stem which carries the valve operating means has been subject to fluid and the action of fluid pressure at all times, when closed, thereby necessitating the provision of means for packing the valve stem against leakage in order to keep the valve structure tight against the escape of fluid present within the container.

The principal objects of my present invention, therefore, are the provision of an improved form of packless valve device; the provision of an improved form of valve device wherein the valve proper is disposed interiorly of the container to be drained and the operating means therefor is disposed exteriorly of such container; the provision of a valve device characterized by this that the stem carrying the operating means is subject to fluid pressure only when the valve is open to establish communication with the container; the provision of an improved valve of the rotating or sliding disc type; the provision in a valve device of a flexible connection between the operating means and the valve device; the provision in a disc valve device of a valve disc so arranged that its point of attachment to the valve stem is so

located as to be at all times within the discharge boundaries of the seat and that such attachment may be flexible; the provision of an improved form of valve device characterized by the fact that there is no fluid pressure within the valve body save when the valve is open to establish communication within the container with which it operates; together with such other objects as may hereinafter appear.

In attaining the stated objects and certain additional benefits and advantages to be below pointed out, I have provided a construction, one embodiment of which is illustrated in the accompanying drawings wherein—

Figure 1 is a front elevational view of a valve embodying my present improvements;

Figure 2 is a sectional view of the device of Figure 1 as taken on the line 2—2 thereof;

Figure 3 is a sectional view taken on the line 3—3 of Figure 2; and

Figures 4 and 5 are front and side elevational views of a modified form of structure.

While my present improvements are to a great extent applicable to either of the types of valves referred to, I find them especially applicable to the type in which the valve itself is disposed inside of the container to be drained, and I have therefore illustrated it as so designed to the end that the stem carrying the valve operating means may be subject to fluid and the action of fluid pressure only when the valve is opened to establish communication with the interior of the container.

Furthermore, while valves embodying my present improvements are obviously of utility for a wide range of purposes, I have, for convenience of illustration, shown them embodied in types of valve structures which may be utilized as blow-off valves for railway locomotive boilers for which purposes they are peculiarly useful.

Referring now more particularly to Figures 1, 2 and 3 of the drawings, it will be observed that I have here shown a form of valve device wherein the valve body 10 is held against the casing 11 of a locomotive boiler by means of bolts 13 passing through said casing 11 and lugs 14 formed on the said body 10.

Within the body 10 is arranged a passage 15, having an inlet port 16 and a discharge terminal 17.

The inlet 16 is closable by means of a valve 18 of a disc type arranged within the casing

11 and arranged to slide from the position shown in full lines in Figure 2 to that shown in dotted lines in such figure and rest upon the marginal seat 18^a and thereby completely 5 cover the inlet 16.

The valve 18, is provided with a socket 19 within which is mounted a stem 20 having a rounded terminal 21 engaging said valve by means of a pin 22, the valve being formed 10 with a housing as indicated at 23, in order that the valve may be held closely against its seat by means of a spring 24, arranged in said housing 23, one end of the spring 24 being attached to said pin 22 and the opposite end attached to a hook 25 carried on such stem 20.

The stem 20 is supported intermediate its ends upon a pintle 26 passed into one side 20 of the casing from the exterior as indicated at 27, the inner end being disposed in a socket 28 in the opposite side of the casing.

At its end opposite to the valve 18, the stem 20 is provided with a conical gear segment 29 with which a conical pinion 31 25 meshes. The pinion is supported at its inner ends by extensions 32 and socketed in the valve body 10.

For operating the valve 18, the pinion 31 has an extension 34 carried in a removable 30 plug-socket 36 and is provided with a terminal 37 upon which an operating lever 38 may be secured. An opening 30 corresponding to the situation of the pinion 31 is closed by a plug 34. When it is desired to so 35 place the lever 38 as to arrange it for left hand operation, the pinion 31 may be placed in the opening 30 for engagement with the pinion 29, upon removal of the plugs 35 and 36.

40 The pinions 29 and 31 are preferably made of conical form in order to translate the rotation of the stem in one plane to the plane in which the operating lever 38 must move.

45 Referring now more particularly to the variant embodiment of my present invention illustrated in Figures 4 and 5, it will be observed that in this form of construction the valve body 10^a is provided with 50 lugs 14^a which may be fastened against the casing 11 by means of suitable bolts.

Within the valve body is arranged a passage 15^a, having an inlet port 16^a, and a discharge terminal 17^a. The inlet is closable 55 by means of a valve 19^a which is mounted on a stem 20^a and secured thereto as indicated at 22^a.

At the right-hand end of the stem 20^a (see Figure 5) there is threaded thereon to 60 a collar 40 upon which is formed a pinion 41 meshing with a gear segment 42 formed on the end of an operating handle 38^a pivoted, as indicated at 43, to an extension 44 formed on the body 10^a.

65 Within the casing is provided a spring

24^a encircling said stem 20^a and abutting at its left-hand end against the interior of said casing 10^a and at its right-hand end against said collar 40 adjacent the point 45, and thereby holding the valve 18^a at all times 70 firmly against its seat on said inlet port 16^a.

Those who are skilled in the art to which my present invention pertains will appreciate that one of the great advantages of the flexible connection between the valve disc 75 and the stem by which it is operated, resides in the fact that friction between the valve and its seat is minimized, and consequently not only does the valve operate more easily but any tendency towards scoring of the valve disc or rounding off of the seat is largely reduced and ensuant leakage prevented.

It will also be apparent that I have provided a flexible connection between the valve 25 stem, the valve itself, and the operating handle, which will permit independent seating of the valve disc without relation to the position of the stem.

Having thus described my invention and 29 illustrated its use, what I claim as new and desire to secure by Letters Patent is:—

1. A packless valve device comprising, in combination, a casing having a passageway and an external seat, a valve adapted to engage thereon, means extending through said passageway for moving the valve laterally relatively to its seat, and a flexible connection between said valve and said moving means and tending to hold the valve on its 100 seat.

2. A packless valve device comprising, in combination, a casing having a passageway and an external seat, a valve adapted to engage thereon, a stem extending through said passageway for operating said valve, means for laterally moving said stem and thereby moving said valve laterally relatively to its seat, and a flexible connection between said valve and stem and tending to 110 maintain the valve on its seat.

3. A packless valve device comprising, in combination, a casing having a passageway and an external seat, a valve adapted to engage thereon, means laterally movable in said passageway for moving the valve laterally relatively to the axis of its seat, and a spring connection between said valve and said moving means.

4. A packless valve device comprising, in combination, a casing having a passageway and an external seat, a valve adapted to engage thereon, a stem movable in said passageway for operating said valve, means for moving said stem laterally and thereby moving said valve in a path laterally relatively to its seat, and a spring connection between said valve and stem.

5. A packless valve device comprising, in combination, a casing having an inlet form-

ing a valve seat, an external valve adapted to seat on said inlet, means for moving the valve in a path laterally relatively to its seat, and means tending to maintain the valve on its seat comprising a flexible connection between said valve and said moving means.

6. A packless valve device comprising, in combination, a casing having an inlet forming a valve seat, an external valve adapted to seat on said inlet, a stem for operating said valve, means for moving said stem laterally relative the casing and thereby moving said valve laterally relatively to its seat, and means tending to maintain the valve on its seat comprising a flexible connection between said valve and stem.

7. A packless valve device comprising, in combination, a casing having an inlet forming a valve seat, an external valve adapted to seat on said inlet, means for moving the valve in a rectilinear lateral path relatively to its seat, and a spring connection between said valve and said moving means.

25 8. A packless valve device comprising, in combination, a casing having an inlet forming a valve seat, an external valve adapted to seat on said inlet, a stem for operating said valve, means for moving said stem in a lateral plane relative the inlet and thereby moving said valve laterally relatively to its seat, and a spring connection between said valve and stem.

35 9. A packless valve device comprising, in combination, a casing having an inlet forming a valve seat, a swinging disc valve adapted to seat on said inlet, means for moving the valve across the seat, and a flexible connection between said valve and said moving means.

45 10. A packless valve device comprising, in combination, a casing having an inlet forming a valve seat, a swinging disc valve adapted to seat on said inlet, a stem for operating said valve, means for moving said stem and thereby moving said valve across the seat, and a flexible connection between said valve and stem.

50 11. A packless valve device comprising, in combination, a casing having an inlet forming a valve seat, a swinging disc valve adapted to seat on said inlet, means for moving the valve across the seat, and a spring connection between said valve and said moving means.

60 12. A packless valve device comprising, in combination, a casing having an inlet forming a valve seat, a swinging disc valve adapted to seat on said inlet, a stem for operating said valve, means for moving said stem and thereby moving said valve across the seat, and a spring connection between said valve and stem.

65 13. A packless valve device comprising, in combination, a casing having a seat, a

disc valve adapted to seat thereon, means for moving the valve relatively to its seat, and a flexible connection between said operating means and said valve, the point of attachment of said connection to the valve disc being so located as to be at all times within the discharge boundaries of the valve seat.

14. A packless valve device comprising, in combination, a casing having a seat, a disc valve adapted to seat thereon, means for moving the valve relatively to its seat, and a spring connection between said operating means and said valve, the point of attachment of said connection to the valve disc being so located as to be at all times within the discharge boundaries of the valve seat.

15. A packless valve device comprising, in combination, a casing having a seat, a valve adapted to seat thereon, means for moving the valve relatively to its seat, a flexible connection between the valve seat and said moving means, and gearing for imparting movement from said moving means through said flexible connection to said valve.

16. A packless valve device comprising, in combination, a casing having a seat, a valve adapted to seat thereon, means for moving the valve relatively to its seat, a spring connection between the valve seat and said moving means, and gearing for imparting movement from said moving means through said spring connection to said valve.

17. A drain valve for containers comprising, in combination, a valve body in fixed relation to the container and having an inlet port within the container, a laterally swinging valve carried by said body and disposed within the container and arranged to be pressed against the inlet port by pressure within the container, and a valve operating means disposed exteriorly of the container and yieldingly connected to the valve, all so arranged that said valve body is free from internal pressure except when the valve is open to establish communication between it and the container.

18. A drain valve for containers comprising, in combination, a valve body in fixed relation to the container and having an inlet port within the container, a swinging disc valve carried by said body and disposed within the container and arranged to be pressed against the inlet port by pressure within the container, and valve operating means disposed exteriorly of the container and yieldingly connected to the valve, all so arranged that said valve body is free from internal pressure except when the valve is open to establish communication between it and the container.

19. A drain valve for containers compris-

- 4
- 15 ing, in combination, a valve body in fixed relation to the container and having an inlet port within the container, a valve carried by said body and arranged within the container to be pressed against the inlet port by pressure within the container, a valve operating means disposed exteriorly of the container, and a substantially universal flexible connection between said valve and operating means, all so arranged that said valve body is free from internal pressure except when the valve is open to establish communication between it and the container.
20. A drain valve for containers comprising, in combination, a valve body in fixed relation to the container and having an inlet port within the container, a valve carried by said body and arranged within the container to be pressed against the inlet port by pressure within the container, a valve operating means disposed exteriorly of the container, and a substantially universal spring connection between said valve and operating means, all so arranged that said valve body is free from internal pressure except when the valve is open to establish communication between it and the container.
25. The combination with a receptacle containing fluid under pressure, of a valve casing having a passage whose inlet is disposed within the receptacle and provided with a valve seat, a swinging valve on the casing within the receptacle and operable to engage said seat, operating means for the valve extending outside the casing, and yielding means connecting the valve to said operating means and normally tending to yieldingly force said valve against its seat with the direction of pressure thereon.
30. 22. A packless valve device comprising, in combination, a casing having a passage and a seat, a valve external of said passageway adapted to engage said seat, means operable in said passageway for moving the valve in a rectilinear plane laterally relatively to the axis of its seat, and yieldingly resistant connecting means between the valve and said means permitting relative independent adjustment of the valve to its seat.
35. 23. A packless valve device comprising, in combination, a casing having an inlet forming a valve seat, an external valve adapted to engage said seat, means for operating the valve in a rectilinear lateral path relative its seat, and means forming a connection between the valve and said operating means for yieldingly forcing the valve upon its seat in the direction of flow through the casing.
40. 24. In a valve device, in combination, a casing having an inlet forming a valve seat, an externally arranged disc valve for engagement with said inlet, means on the casing for moving said valve into registration with the inlet to close the same, and a yieldingly resistant substantially universal joint between said means and the valve for permitting limited relative movement of the valve and means tending to maintain said valve on its seat.
45. 25. In a valve device, in combination, a casing having an inlet forming a valve seat, an externally arranged disc valve for engagement with said inlet seat, means non-axially arranged in said casing for moving said valve into registration with the inlet to close the same, and a yieldingly resistant connection between said valve and moving means.
50. In testimony whereof I have hereunto signed my name.
55. THOMAS W. DEMAREST.
